Alt. 150.

UNITED STATES PATENT OFFICE

WILLIAM KLUG, OF CHICAGO, ILLINOIS, ASSIGNOR TO NOVELTOY CORPORATION, OF CHICAGO, ILLINOIS, A CORPORATION OF ILLINOIS

DESIGN FOR A COMBINED PONY AND RIDER TOY

Application filed July 12, 1930. Serial No. 36,334. Term of patent 3½ years.

To all whom it may concern:

Be it known that I, WILLIAM KLUG, a citizen of the United States, residing at Chicago, county of Cook, and State of Illinois, have invented a new, original, and ornamental Design for a Combined Pony and Rider Toy, of which the following is a specification, reference being had to the accompanying drawings, in which—

pony and rider toy and Figure 2 is a front view on a reduced scale, showing my new design. The opposite side of the toy presents a similar appearance to the one shown in Figure 1.

I claim:

The ornamental design for a combined pony and rider toy, as shown and described.

WILLIAM KLUG.
